JOHN W. KLENSCH, JR., AND ARTHUR E. KLENSCH, OF FOREST HILLS, NEW YORK

CONICAL GRATER

Application filed September 13, 1928. Serial No. 305,804.

This invention relates to grating apparatus, and more particularly to power graters utilizing a conical grating element.

It is an object of the invention to provide an improved device of the character set forth, in which an improved removable conical grating element is provided.

A further object of the invention is to provide in a device of the character described, a removable grating chamber which is provided with a plurality of radially extending barriers adapted to retain the material to be grated against the grating surface.

A further object of the invention is to provide in a device of the character described, a chamber adapted to receive the grated material, said chamber being at all times in communication with the grating surface, said chamber being provided with means whereby the grated material may be removed from the chamber.

Other objects of the invention include the combination and interrelation of parts, whereby the whole forms an improved, efficient apparatus which will be economical to construct and easy to operate.

Numerous other objects and features of the present invention will be apparent from a consideration of the drawings, in which—

Fig. 1 is a top plan view of one form of my present invention.

Fig. 2 is a side elevation partly in section of that form of the invention illustrated in Fig. 1.

Fig. 3 is a vertical sectional view of the grating chamber removed.

Fig. 4 is a view partly in section of the grating element.

Fig. 5 is a detail view showing the structural features and assembly of the apparatus.

Referring more particularly to the drawings, there is provided a base 10 through which extends a driving shaft 11, the outer ends of which may be provided with suitable driving pulleys 12, and intermediate the ends of which the bevelled driving gear 14 is provided; shaft 11 is preferably journalled in diametrically opposite sides of the casing 10 as at 15, and is also preferably centrally jour-

naled at 16 in a vertically extending journal member 17, in the top of which a vertical driving shaft 18 is journalled being provided with suitable thrust bearings as at 19. The vertical shaft 18 is provided with a cooperating bevel gear 20, and it may readily be seen that by cooperation of the gears 14 and 20, the vertical shaft 18 is caused to rotate in response to the applied forces on the pulley wheels 12.

A suitable shaft and gear housing is provided for the gears 14, 20, shaft 11 and a portion of the vertical shaft 18. This housing includes an under pan 21 which is provided at its center with the member 17, and with a cooperating cover which includes a frusto-conical central portion 22 and an inclined floor 23.

Within the housing, suitable lubricants may be provided. If desired, the entire housing may be packed with lubricating grease.

It will be noted from further consideration of the invention that the housing prevents the contact of the grated material with the necessary lubrication for the gearing and shafts. It will also be noted that the upper surface of the floor 23 and conical member 22, together with the under pan 21 form a tubular housing for the shafts 11 and 18 and the gears 14 and 20, but which provide space for the passage of grated material between the walls 10, whereby it may come to rest and be received upon the top 24 of a suitable supporting surface for the apparatus.

Mounted upon the casing 10 and removably secured thereto by the provision of bifurcated extending lugs 25 and a cooperating bolt and wing nut assembly 26 secured to the housing 10, a grating chamber is provided including vertically extending side walls 27, and inward extending baffle members 28 which join at the top to form a seat for an inserted bearing 29 for the upper end of the vertical shaft 18. The baffles 27 taper downwardly to provide a conical free space within the grating chamber. The baffle members 28 are inclined toward their bottom in the direction of the rotation of the conical member, whereby there is provided an inclined surface tending to urge the material to be grated

downwardly and forcing it in contact with the grating surface.

Within the free space and slightly spaced from the inner edges of the baffles 28, there is provided a grating element 30 which comprises a central vertical bore 31 adapted to receive the shaft 18 from which extend radially supporting members 32 and a conical surface 33 which is supported at its lower 10 end by the members 32. The lower end of the central portion is grooved as at 34 to be received upon a pin 35 of the shaft 18, whereby rotation of the shaft 18 will effect rotation of the grating element 30. A removable 15 grating surface 36 is provided over the sides 33 of the grating element, and may be crimped as at 37 about the lower edge thereof for securing it rigidly thereto.

By referring to Figs. 2 and 5 of the drawings, it will be noted that the grating element 30 is positioned in slightly spaced relation to the radial members 28 and the side walls 27, the grating material being supplied through the open top of the grating chamber and between the radial members 28. Rotation of the grating element 30 causes contact of the material to be grated as indicated at 38 with the grating surface 36, and the material after grating moves downwardly 30 over the conical surface, passing between the lower edge thereof and the walls 27, and into the chamber within the body 10 from which it may be removed, and is received upon the surface 24.

35 Thus, it may readily be seen that we have provided an apparatus of simple and improved construction for readily carrying out the objects of the invention as herein recited. It will be readily understood that numerous 40 changes and modifications of the invention may be resorted to without departing from the spirit or scope of the appended claim.

We claim:

In a device of the character described, a 45 receptacle for receiving grated material, a grating chamber detachably superposed thereon, driving mechanism within said receptacle, said driving mechanism including a horizontal drive shaft extending through 50 said receptacle and journaled in diametrically opposite sides thereof, a bevelled driving gear intermediate the ends of said horizontal shaft, a vertical drive shaft extending through said grating chamber, a bevel 55 gear provided at the lower end of said vertical shaft, cooperating with said bevelled driving gear, a housing for said driving mechanism, a removable conical grating surface carried by said vertical drive shaft adapted 60 to rotate therewith, and stationary radially extending baffle members within said grating chamber carried thereby for association with said conical grating surface, said baffle members being joined at their tops, forming a 65 bearing for one end of said vertical drive

shaft, said baffle members being inclined in the direction of rotation of said grating surface for forcibly directing the material to be grated into contact with said conical grating surface.

JOHN W. KLENSCH, JR.
ARTHUR E. KLENSCH.
